UNITED STATES PATENT OFFICE.

GIUSEPPE E. TERRANOVA, OF NEW HAVEN, CONNECTICUT.

MUSICAL TOY.

1,414,446.

Specification of Letters Patent.

Patented May 2, 1922.

Application filed June 2, 1921. Serial No. 474,384.

To all whom it may concern:

Be it known that I, GIUSEPPE E. TERRANOVA, a citizen of the United States, residing at New Haven, in the county of New Haven and State of Connecticut, have invented a new and useful Improvement in Musical Toys; and I do hereby declare the following, when taken in connection with the accompanying drawings and the characters of reference marked thereon, to be a full, clear, and exact description of the same, and which said drawings constitute part of this application, and represent, in—

Fig. 1 a side view, partly in section, of a musical toy constructed in accordance with my invention.

Fig. 2 an inside face view of part of the back of the casing, illustrating a spring-operated music-producing device and means operated thereby.

This invention relates to improvement in musical toys, and particularly to musical toys including a figure, the object being to produce a toy simulating a player-piano with a figure operating it, and the invention consists in the construction as herein-after described and particularly recited in the claims.

In carrying out my invention, I employ a casing 5 simulating, in appearance, an upright piano mounted upon a base 6. The back 7 of the casing has mounted upon it a music-producing device 8, as commonly employed in music boxes, and which is spring-operative and wound by a key 9. This music-producing device includes a shaft 10 on which a pulley 11 is mounted. Above the device is a drum 12 covered with paper dotted to simulate the appearance of a perforated music roll sheet, and this drum is driven from the pulley 11 by a belt 13, the face of the drum showing through an opening 14 in the front board 15 of the casing. Near the bottom of the back board 45 is mounted a crank-shaft 16 having two cranks 17 and 18, the shaft being turned from the pulley 11 by a belt 19. These cranks 17 and 18 engage with pedals 19 and 20, so that the pedals will be moved by the operation of the music-producing device. Seated upon a bench 21, in front of the casing, is a doll 22, the feet of which rest upon the pedals 19 and 20, being held

thereon by sockets 23 into which the toes extend.

If desired, a connecting rod 24 may be coupled with one of the cranks 17 or 18 and extend forward into engagement with a crank 25 formed at the lower end of a rod 26, extending upward through the body 60 of the doll and connecting with the head 27 thereof, so that the head may be turned from side to side. The music-producing device being wound, will produce musical sounds and, at the same time, the drum 12 65 will be turned so as to give the appearance of a music roll sheet above the key-board. At the same time, the cranks 17 and 18 will be turned, so as to raise and lower the pedals 19 and 20, so that it appears that the 70 doll is operating the player-piano, and if the connecting-rod 24 is employed, it will turn the crank 25 at the end of the vertically-arranged rod 26 so as to turn the head 75 of the doll.

I thus produce, in a very simple way, the simulation of a player-piano being operated by a doll, producing an attractive toy.

I claim:

1. A musical toy, comprising a casing, 80 formed in its front face with an opening and provided with a back, a spring-operated music-producing device mounted in the said casing, said music-producing device including a shaft, a drum representing 85 a perforated music-roll supported in the casing in line with the opening in the front thereof, cranks mounted near the bottom of the casing, pedals resting on said cranks and adapted to be raised and lowered thereby, 90 connections between said shaft, drum and cranks whereby they are moved with the said shaft, and a doll mounted in front of the casing and having feet resting upon said pedals and adapted to move therewith. 95

2. A musical toy, comprising a casing, formed in its front face with an opening and provided with a back, a spring-operated music-producing device secured to said back, said device including a shaft, a pulley 100 on said shaft, a drum supported by said back in line with the opening in the front of the casing and turned by said pulley, cranks mounted on said back near the bottom thereof, and also turned from said pulley, 105 pedals raised and lowered by said

cranks, a doll mounted in front of the casing and having feet resting upon said pedals, the head of the said doll mounted upon the upper end of a vertical rod, a 5 crank at the lower end of the rod, and a connecting-rod between said last named crank and one of the pedal cranks.

In testimony whereof, I have signed this specification in the presence of two subscribing witnesses.

GIUSEPPE E. TERRANOVA.
